His Attorney

UNITED STATES PATENT OFFICE

WILHELM PFANNKUCH, OF COPENICK-WENDENSCHLOSS, GERMANY, ASSIGNOR TO
GENERAL ELECTRIC COMPANY, A CORPORATION OF NEW YORK

JOINT FOR HIGH TENSION ELECTRIC CABLES

Application filed October 14, 1929, Serial No. 399,435, and in Germany March 15, 1929.

As is well understood, high tension cables are made in moderate lengths for manufacturing reasons, and are subsequently jointed or spliced after installation. Such cables are commonly insulated by tightly winding strips of paper layer by layer around the conductor by a suitable machine, until the necessary thickness of insulation is provided, after which a lead sheath is applied. In making the joints, the factory wound insulation is entirely removed for a short distance at the ends of adjacent lengths to receive a connector or sleeve which is soldered or otherwise secured to said ends. Insulation is removed from the conductor ends either by what is known as penciling or step-by-step, the net effect being to taper the insulation with a long taper from the connector to the full diameter of the insulation. Subsequently, the connector and the tapered ends of the insulation are wrapped with strips of paper or equivalent material to a diameter substantially larger than that of the factory wound insulation. The penciling method is not very favorable because of the difficulty in winding the insulation properly over the smooth conical surfaces. On the other hand, the step-wise reduction has the disadvantage that it is only possible to attain favorable results when the number of steps is relatively great, which again is objectionable because of the lack of simplicity and because of the increased cost. Furthermore, if the number of steps is restricted and each step of necessity made correspondingly great, intermediate spaces, gaps or voids are formed or occur at the shoulders of the steps and which extend radially. If these voids are not perfectly filled with impregnating fluid when the joint is being made, they later give rise to intense ionization when the cable is in operation, which leads to a rapid destruction of the joint as a whole.

My invention has for its object to overcome the objections above noted, and to provide in high tension electrical apparatus having bodies of separately applied insulation means for preventing glowing and arcing at the joints between the bodies. More specifically, my invention has for its object the provision in a cable joint of the step type of means for

preventing injurious electrical effects at the steps where the factory wound insulation makes a sudden and substantial change of diameter.

For a consideration of what I believe to be 55 novel and my invention, attention is directed to the accompanying description, and the claims appended thereto.

In the drawing which is illustrative of my invention, Fig. 1 is a longitudinal section of 60 a high tension cable joint, and Fig. 2 is a slight modification thereof.

3 indicates a stranded conductor which may be hollow or solid as desired. The ends of the two adjacent lengths are united by a metal 65 connector 4 of sleeve formation, said parts being soldered or otherwise united to form a good electrical and mechanical union. 5 indicates the insulation on the conductor and is composed of rather narrow strips or ribbons 70 of paper wound layer by layer thereon with overlapping joints. This is done by any suitable machine. The paper is impregnated with oil or a suitable compound, usually after the cable is completed. Outside the insulation is an enclosing sheath 6 made of lead or equivalent material to prevent the entrance of air and moisture and the escape of the impregnating material.

In order to properly insulate the joint, the 80 factory wound insulation on each cable end is removed in such manner as to form relatively large steps. The invention is not limited to any definite number of steps since this will depend largely upon the potential 85 at which the cable is designed to operate, and upon the thickness of insulation. As a general proposition, however, it may be stated that the number of steps is relatively small. With a prior construction, for example, of 90 which I have knowledge it is customary to provide as many as eighteen steps on each of the adjacent ends of a 132 KV cable, or a total of thirty-six. As illustrated, there are three steps, that is to say, the first from 95 the conductor to part 7, the second from part 7 to 8, and the third from part 8 to 9, which latter has the full diameter of the cable insulation. At each step a shoulder is formed, and the annular facial surface is, according to my 100

- invention, provided with an annular metallic covering 10. Without this covering there would be small gaps between the factory wound insulation and the edges of the tape or second body of insulation which is subsequently applied to the joint. These gaps would extend in the direction of the electric field about the conductor or at a slight angle thereto. Stated in another way, there are 10 two bodies of insulation both of which are wrapped around the conductors in concentric layers with the edges of the layers of the second body in abutting relation with those of the first at each step, and interposed between these abutting edges are annular elements which form short circuiting devices. It is important that these coverings be annular since otherwise there would be a high concentration of stresses at any joint therein. 15
- 20 Where the pressure or potential differences between the steps is for any reason not very great, semi-conducting material may be used for the coverings instead of metal. These coverings, whether of one kind or the other, 25 are advantageously made of thin soft material which can readily be formed to the required shape either prior to or after being mounted in position. The coverings, for the purpose of illustration, have been exaggerated 30 in size and especially in thickness. Each covering is provided with cylindrical or flanged portions 11 which fit snugly over the adjacent parts of different diameters and which are united by a ring-like portion 12 that abuts 35 the cut end of the factory wound insulation. These metallic coverings or coatings are independent of each other, in other words, are isolated one from the other, and are not connected to ground and consequently each assumes 40 an intermediate potential due to capacity conditions. Each of these coverings forms a metallic short circuiting device between the part or portion of smaller diameter and the part or portion of larger diameter 45 of the cable. The absolute strength of the insulating layer at each of these points or regions is somewhat decreased by reason of the covering, but this is compensated for by correspondingly increasing the amount of insulation 50 which is applied over the joint. These metal coverings prevent all glowing or arcing at the face surface of the steps, and on that account even if a small void at such step should exist, and which is not filled by 55 the impregnating compound, it will no longer have an appreciable destructive action.
- 60 After the steps have been formed in the factory wound insulation and the coverings applied to each step or shoulder, the joint is taped with impregnated paper tape 13 or equivalent material so as to completely fill all of the spaces and assemble about the joint the necessary amount of insulation. This will 65 include what may be termed the normal amount of insulation plus that amount which may be necessary to compensate for the presence of the conducting or semi-conducting coverings 10. Surrounding the joint is a casing or enclosure 14 which is suitably united at its ends to the sheaths 6 of the adjacent 70 cable lengths.
- In Fig. 2 is shown a slight modification of the invention, wherein the coverings 10 are applied to the ends only of the steps instead of having cylindrical parts or flanges which 75 embrace the adjacent cylindrical surfaces of the parts of the cable. In effect they form rings which fit over the smaller parts and at their peripheries are flush with the surface of the next larger part. These also may be 80 made of some thin and relatively soft material so as to occupy a small space and snugly fit the insulation.
- The invention is not only advantageous for cable joints of the character hereinbefore referred to, but also for other constructions where it is important to prevent the disadvantageous influence of layers or of gaps in the insulating material, which extend in the direction of the electric field about a conductor or at a slight angle to the same within 85 the insulating covering.
- 90 Looking at the matter from one point of view, a conductor is provided which carries current of high potential and which is enclosed in a casing of much lower potential, usually that of the earth, and between the two is a body of insulation composed of two parts, one of which is applied initially in the manufacture and is machine wound, and the 95 other applied subsequently and which, no matter how it is applied, is distinctly separate from the first, and to prevent glowing at the edges or the joints between the two insulations a metallic element is interposed.
- 100 What I claim as new and desire to secure by Letters Patent of the United States, is:
1. In a cable joint, the combination of a pair of conductors, insulation on each of the conductors which is arranged in concentric layers, said insulation being cut away toward the adjacent end of the conductors by a series 105 of steps, each of which is equal in depth to a number of layers of insulation, a connector for uniting the conductors, a wrapping of insulation also arranged in concentric layers and covering the joint between the conductor insulations, and short circuiting devices located between the two bodies of insulation 110 where their edges are in abutting relation.
- 115 2. The combination of a current carrying conductor, a casing therefor and separate bodies of insulation which are wrapped around the conductor in layers, one of said bodies being cut away to form steps, with 120 conducting elements located at the steps where the edges of the two bodies are adjacent, each of said elements comprising a portion located between said edges and other 125

portions which overlie the insulation at the bottom and top of the step.

3. In a joint for high tension cables, the combination of a pair of conductors, each of which has a body of factory-wound insulation thereon, the diameter of which is reduced step-by-step toward the ends, a connector for uniting the ends, a short circuiting device located at each step, said devices being electrically independent of each other, a second body of insulation which is wound over the connector, devices and a portion of the factory-wound insulation, and a metallic enclosure for the joint and cable.

10 15 In witness whereof, I have hereunto set my hand this 30th day of September, 1929.

WILHELM PFANNKUCH.
